SHEET METAL COVERED ROOF

Alois W. Pattiani, Oakland, Calif.

Application February 23, 1938, Serial No. 191,857

18 Claims. (Cl. 108—13)

This invention relates to the sheet metal covering of roofs of the type where the metal is very thin and is made to conform more or less to the physical or structural surface of the supporting roof immediately below the sheet metal. The principal object of the invention is to provide improvements in such roofs which make it easier and quicker to apply the sheet metal, also which produce a better external appearance which may 5 be varied considerably, and also a sheet metal roof system more adapted to meet the exigencies met with in old roofs which it is desired to cover with thin sheet metal.

Other objects and advantages of the invention 10 will appear in the following description and accompanying drawings.

In the drawings:

Figure 1 is a perspective view of a portion of a slanted roof constructed in accordance with one 15 modification of my invention and partly covered with thin sheet metal in accordance with the invention.

Figure 2 is an enlarged vertical section of the completed roof.

Figure 3 is a vertical cross section of one joint or horizontal seam of the sheet metal covering and the wood-work adjacent thereto, all shown 20 greatly enlarged over Figure 2.

Figure 4 is a view similar to that of Figure 3, 25 but shows a modified form of the joint.

Figure 5 shows a further modification from that of Figure 3.

Figure 6 shows a still further modification.

Figure 7 is a vertical section of a roof similar 30 to that of Figure 2, but shows the application of the invention to an existing shingle roof or other solid covered roof having a similarly stepped outer surface.

Figure 8 is an enlarged detail of the joint of 35 the roof of Figure 7.

Figure 9 shows a further modification over the arrangement shown in Figure 2.

Briefly described the roof may be said to be 40 of the general type shown in the expired Patent No. 899,022 wherein overlapping roof boards or shingles are covered with horizontally extending sheets of thin sheet metal except that the horizontally extending joints between the metal sheets are not held down by overlying boards or shingles as in the patent mentioned, which 45 makes it necessary to build both the supporting roof as well as the metal covering progressively from the bottom up, but the joints are more like the joints in the metal covered roof in Patent No. 1,664,261, except that no special tapered roof 50

boards are required as there shown, the joint provides for stretching the metal into the corners and relieves the thin sheet metal (usually paper-thin soft copper) from any strain against nail or tack heads so easily torn out as with the construction shown in the latter patent, but in its preferred form entirely avoids any nails through the folded metal joint, and also provides for producing a variety of pleasing exterior appearances, for in its complete form the invention produces a 10 thin sheet metal covered roof with large regular or irregular waves running horizontally, and to a certain extent vertically also, and further provides undulating deep shadow effects not heretofore obtainable in a roof of this kind. 15

In the showing of Figure 1 the roof comprises a series of horizontally extending overlapping boards 1 which are in the nature of ordinary clapboards nailed to rafters 2 or any other suitable supporting roof structure, though the word 20 "boards" is here intended to include either wooden or artificial boards as of "Celotex" and other fiber bodies.

The boards are, of course, laid from the bottom of the roof up, and as each is nailed in place, 25 vertically extending strips 3 of wood or other material are spacedly secured to them, as by nailing or otherwise, so that the next board above will overlap the upper end of the strip and thereby be forced to bend or arch upward as indicated 30 at 4 in Figure 1 so that each board is alternately arched up and down numerous times throughout its length. The effective height of the arches then formed may be increased by having the vertical strips of wedge or tapered form starting 35 quite thin at their lower ends as at 3' and becoming several times as thick at their upper ends as at 3''. If desired the securing nails 5 for the strips 3 may extend through the overlapping "weather boards" 1, and into the rafters 2, as indicated in Figure 3 at the point where the strips occur, or the boards may be nailed to the rafters independently of the strips, and the latter nailed only to the board immediately below. 40

In Figure 1 the spaced vertical strips are shown 45 evenly staggered with respect to the strips of adjacent boards, but the strips may be unevenly spaced, or irregularly positioned to produce any desired exterior appearance of the roof, or they may be omitted entirely insofar as some features 50 of the present invention are concerned, or other artifices may be employed to vary the ridges or shadow lines of the roof as will be hereinafter explained, or the strips may be varied from the vertical. 55

After the roof structure is completed as shown in the left-hand portion of Figure 1, with or without the spaced strips, the copper or other thin metal sheets 6 are applied, beginning with the lowermost edge of the roof. The sheets or strips of metal are preferably of paper-thin ductile copper of about the width of the boards 1, and are extended parallel with them. The lower edge of the first sheet may be wrapped under the lower edge of the lowermost board and secured in place, or it may be secured to the upwardly projecting edge 1' of the boards in conformity with succeeding edges of the sheets at succeeding boards in the manner shown in Figure 2, and further detailed in Figure 3.

In the figures the successive sheets of copper are designated 6, 6¹, 6², 6³, etc., and in Figure 3 it will be seen that the upper margin of one sheet and the lower margin of the next sheet above are bent and doubled over as shown at 7 to lie against the upstanding edge 1' of the board above and then secured against it as by a strip of wood 8 held in place by nails 9 passing into the edge of the upper board above the folded metal joint.

In applying the metal, the second sheet is laid flat on the first sheet and their margins folded together either once as shown in Figure 3, or twice if desired, the strip 8 is placed against the seam and nailed in place to draw the metal firmly up into the corner so as to take up any slack in the lower sheet. After this, the second sheet 6' is bent up and over strip 8 and nails 5, 9, and extended up to the lower edge of the next board, and the operations repeated. Any necessary joining or piecing of one of the horizontal strips or sheets of copper may be made in any approved manner as by folding and/or soldering.

After the whole roof is covered in the manner described, or progressively as it is covered, the thin soft copper sheets are pressed down around the sides of the strips 3 and along the undulations of the boards (either with the fingers of a gloved hand, or with a felt pad or stiff brush). The sheets of metal may be extended over the ends of the boards and secured in any desired manner, and any suitable cap or sheet of metal may be used to straddle the gable of the roof, or the two final sheets of metal from both sides may be simply brought together and folded over two or three times, and soldered if desired.

By reference to Figure 3 it will be noted that strip 8 is shown with its inner face beveled off to accommodate the thickness of the folded metal seam or joint and form a "heel" 8' at the upper edge of the strip on which the strip fulcrums when the nail is driven in, and thus draws or forces the metal seam tightly up against the edge 1' of the board. The thickness of the metal seam is greatly exaggerated in the drawings as the metal used is preferably only of paper thickness, and therefore the beveling of the strip, if used, need be very little. Strips 8, of course, follow the undulating edges of the boards in passing over strips 3 if the latter are used, or may be cut to more or less follow the undulations of the board if desired.

The modification shown in Figure 4 varies from that of Figure 3 in showing the two metal sheets simply bent upward to lie against the edge 1' of the board and tacked in place as with small nails 10, and then drawn up or stretched into the corner with the strips 8 secured with larger nails 11 which may pass directly through both layers of copper. The slight space 12 shown in the corner

may be entirely taken up in stretching the metal with the aid of the strips 8. It is of course evident that in the joint of Figure 4 the edges of the metal sheets may be folded or doubled over each other one or more times, if desired, as shown in the other figures.

In the form shown in Figure 6 the joint is substantially like that shown in Figure 4 except that strip 8 is not beveled, and wedge-shaped boards 20 are arranged with their thickest edges 20' at the bottom, and also in overlapping relation to strip 8. This modifies the outward appearance of the roof when covered with metal. In this form the spaced strips 3 of Figure 4 may also be used if desired.

In Figure 5 the folded metal seam 12 is held in place by means of a thin metal or other angle bar 13 which overhangs the corner of the upper board and is forced tightly against the seam to clamp it against the edge 1' of the board and then nailed from above as by nails 14 which may be started at a slant so as to draw the angle bar up tightly and force the seam into the corner. These angle bars are preferably continuous along the edge of the board, and they give great support and protection to the thin sheet metal at the corners of the boards against injury from anyone walking on the roof for any reason.

The showing of Figure 9 is substantially the same as that of Figures 1 to 3 except that the vertical strips 3 are extended clear under the next board above as shown at 3'', and this view also shows the boards resting against purlins 15 instead of the rafters 2, though this feature is optional.

In Figures 7 and 8 the application of the invention to a shingled roof is shown and wherein the shaded stepped member 16 designates a shingled roof supported on purlins or spaced sheathing 17 and rafters 18 in the usual manner, while at the forward end of every other row of shingles is nailed a board 19. This board is of a thickness equal to the lower ends of the shingles and of a width to preferably abut the edges of one row of shingles, and come flush with the lower row to thereby accomplish several things; first, to create a higher ridge; second, to double the length of the "exposure" so that with shingles laid four inches to the weather the flat steps will be eight inches; and third, to give a cross grain nailing surface for the seam or metal joint tensioning strips 8 which are applied in the manner described. The joint of the metal sheets may, of course, be folded over one or more times, or simply lapped as previously described. Boards 19 may be thicker at their lower edges as shown for boards 20 of Figure 6, if desired, or the latter may additionally be used.

Instead of the stepped members 16 being an existing shingle roof, it may of course be a weather board roof laid up to produce the steps shown, but it would usually represent an old shingled roof which it was desired to sheath over with thin copper by the method of the invention.

In considering the invention and its modifications above described, it should be noted that its chief advantage over metal covered roofs as shown in such patents as Benson No. 899,022 and Wright No. 2,081,191, is that it permits the foundation woodwork to be first completed before the copper is applied, thus making it safer and much quicker to apply, and above this it produces a variety of roof surfaces impossible to secure in these earlier constructions.

It is also evident that while the invention has

its principal application to roofs, yet it may also be as readily applied to the sides of buildings, and the word "roof" as used in the claims is to be understood as embracing any outer surface of a building to which the invention is applied. 5 If the roofs are of very little pitch, the sheet metal joints may be white-leaded as they are folded, if desired. Also to be noted is that the very thin sheet copper or other metal used may be backed with paper to which it may be glued or cemented, if desired, as this would not affect the principle of the invention. Also to be noted is that my use of the words "board" or "boards" 10 in the claims as denoting the substantial or solid roof covering or foundation upon which the copper is secured, is intended to include boards of wood, or artificial boards of fiber, or other materials, and also shingles.

Having thus described my invention, several of 20 its possible modifications, and the manner of carrying it out, what I claim is:

1. In a slanted roof provided with a covering of boards one above the other presenting upstanding horizontally extending lower edges of the 25 boards, horizontally extending paper thin metal sheets covering the outer surfaces of the boards formed with connecting seams respectively positioned against said lower edges, a clamping strip extending longitudinally of and outside of each seam and secured to the boards, and one sheet of 30 the metal extending from said seam under, around, and over said clamping strip and board above and joined by a seam as above described by another sheet of metal at the lower upstanding edge of the next board above in repetition in 35 the manner described.

2. In a slanted roof provided with a covering of boards one above the other presenting upstanding horizontally extending lower edges of the 40 boards, horizontally extending paper thin metal sheets covering the outer surfaces of the boards formed with connecting seams respectively positioned against said lower edges, a clamping strip extending longitudinally of and outside of each seam and secured to the boards, and one sheet of 45 the metal extending from said seam under, around, and over said clamping strip and board above and joined by a seam as above described by another sheet of metal at the lower upstanding edge of the next board above in repetition in 50 the manner described, said clamping strips formed and arranged to facilitate drawing the seam of the joined metal sheets into the outside corner formed by juncture of the boards.

3. In a slanted roof provided with a covering 55 of boards one above the other presenting upstanding horizontally extending lower edges of the boards, horizontally extending thin metal sheets covering the outer surfaces of the boards formed with connecting seams respectively positioned against said lower edges, a clamping strip 60 extending longitudinally of and outside of each seam and secured to the boards, and one sheet of the metal extending from said seam under, around, and over said clamping strip and board above and joined by a seam as above described by another sheet of metal at the lower upstanding 65 edge of the next board above in repetition in the manner described, the clamping strips secured to their respective boards by nails passing into the edges of the boards.

4. In a slanted roof provided with a covering 70 of boards one above the other presenting upstanding horizontally extending lower edges of the boards, horizontally extending thin metal

sheets covering the outer surfaces of the boards formed with connecting seams respectively positioned against said lower edges, a clamping strip extending longitudinally of and outside of each seam and secured to the boards, and one sheet of 5 the metal extending from said seam under, around, and over said clamping strip and board above and joined by a seam as above described, by another sheet of metal at the lower upstanding edge of the next board above in repetition in 10 the manner described, said clamping strips secured to their respective boards by nails passing into the edges of the boards at a point above and to clear said seams.

5. In a roof as described in claim 1, means 15 spaced along said boards forming successive arches of and along the boards.

6. In a roof as described in claim 1, means 20 spaced along said boards forming successive arches of and along the boards and staggered 20 with respect to adjacent boards.

7. In a slanted roof provided with a covering of 25 boards placed parallel to one another, means forming successive arches in the boards spaced along their lengths.

8. In a slanted roof provided with a covering of 30 boards placed parallel to one another, means forming successive arches in the boards spaced along their lengths, and staggered with relation to adjacent boards.

9. In the construction set out in claim 7, a sheet 35 metal covering over said boards conforming substantially to the arched surface of the boards.

10. In the construction set out in claim 8, a sheet metal covering over said boards conforming 40 substantially to the arched surface of the boards.

11. In a slanted roof provided with a covering 45 of horizontally extending boards placed parallel to one another, spaced vertically arranged strips over which the boards are sprung to form successive arches along the boards.

12. In a slanted roof provided with a covering 50 of horizontally extending boards placed parallel to one another, spaced vertically arranged strips over which the boards are sprung to form successive arches along the boards, said strips being thicker at one end than at the other.

13. In a slanted roof provided with a covering 55 of horizontally extending boards placed parallel to one another, spaced vertically arranged strips over which the boards are sprung to form successive arches along the boards, said strips being thicker at their upper end.

14. In a structure as set out in claim 1, said 60 clamping strip being an angle bar overlapping the upper corner of the lower edge of the board.

15. In a shingled roof, horizontally extending 65 boards abutting the lower ends of a row of shingles and terminating substantially flush with the lower end of the row below, said boards being substantially the thickness of the shingles which they abut and provided with means securing them in place, a sheet metal covering for the roof formed with horizontally extending seams positioned against the lower edges of said board and means securing said seams in place.

16. In a shingled roof, horizontally extending 70 boards abutting the lower ends of a row of shingles and terminating substantially flush with the lower end of the row below, said boards being substantially the thickness of the shingles which they abut and provided with means securing them in place, a sheet metal covering for the roof formed with horizontally extending seams positioned against the lower edges of said board, and 75

a clamping strip at the outer side of each seam provided with means holding it to said board for securing said seams in place.

17. A sheet metal covered roof provided with a foundation having horizontally extending ridges spaced one above the other, and wavy arches following each other horizontally between said ridges.

18. A sheet metal covered roof provided with a foundation having horizontally extending ridges spaced one above the other, and wavy arches following each other horizontally between said ridges, and said arches staggered with relation 5 to the arches between adjacent ridges.

ALOIS W. PATTIANI.
